UNITED STATES PATENT OFFICE.

SAMPSON W. MOON, OF CHICAGO, ILLINOIS.

ELECTRIC SAFETY RAZOR.

Application filed September 1, 1926. Serial No. 132,963.

My invention relates to electric safety razors of the type disclosed in my Patent No. 1,592,309 of July 13, 1926. The object of the invention is to modify and simplify 5 the construction and arrangement, and to make the device more accessible for inspection, repairs or replacements.

The various features of the invention are embodied in the device shown on the drawing 10 in which:

Fig. 1 is a side elevational view;

Fig. 2 is an enlarged sectional view on plane 2—2 Fig. 1;

Fig. 3 is a sectional view on plane 3—3 15 Fig. 2;

Fig. 4 is an enlarged sectional view on plane 4—4 Fig. 2, and

Fig. 5 is an enlarged sectional view on plane 5—5 of Fig. 2.

20 The structure shown comprises a magnetic frame having the legs 10 and 11 extending from the head or yoke 12 in the form of a disc, the ends of the legs being secured to a foot piece 13 in the form of a plate. The legs and the head form a magnetic frame which is permanently polarized, and the plate 13 is of non-magnetic material, the outer ends of the legs then forming magnetic poles.

25 A vibratory member or armature in the form of a bar 14 extends parallel with the legs 10 and 11 and at its front end is rigidly attached to the rear end of a flat spring 15, as by rivets 15', said spring at its front end being anchored in the slot 12' in the head 12, the armature bar being thus adapted for lateral vibration. An energizing winding 16 for the armature bar is shown wound on the bar between the insulating 30 end washers 17 and 18, and the outer end 19 of the armature bar is deflected to extend between the outer or pole ends of the magnet frame legs 10 and 11. The armature bar is of soft iron.

35 A distance rearwardly from its anchored end a tongue 20' extends from the spring 15 and is secured in the slot 20" in the supporting bar 20 which extends axially through the hole 21 in the head 12, the bar at its 40 outer end being threaded for the reception of a coupling fitting 22 by means of which

tools such as a shaving head 23 may be applied to the rod 20. If the tool has the proper threading it can, of course, be applied directly to the end of the rod without the 55 interposition of the coupling fitting 22.

Secured to the plate 13 against the outside thereof is a circular disc or block 24 of insulating material. This block supports the terminal pins 25 and 26. The pins at their 60 outer ends are close to the axis of the block and are parallel for the reception of an extension cord socket (not shown). The intermediate sections *a* of the pins extend diagonally through the block and the inner 65 ends *b* extend through a spacer and anchoring piece 27 held against the inner side of the block 24, the terminals 28 and 29 of the energizing winding 16 being soldered to the 70 terminal pins just inside of the piece 27.

When the energizing winding is connected by means of the terminal pins and extension cord with an alternating current circuit, the armature bar will be rapidly vibrated on account of the attraction between its end 19 75 and the adjacent permanent magnetic poles of the magnet frame legs 10 and 11. The bar 20 projecting from the spring tongue 20' will partake of the armature bar vibration and the tool 23 will be laterally oscillated. 80 In order to prevent striking or sticking of the armature end against these legs, abutments or bumpers 30 in the form of short lengths of rubber tubing are supported on the pins 31 and 32 extending from the plate 85 13 at opposite sides of the armature ends. These rubber bumpers will take the blows of the armature and prevent noise, and are readily accessible and when worn out can be readily replaced. The bumper supporting 90 pins can be readily bent so that accurate adjustment can be made of the bumpers relative to the armature.

In order to protect the operating parts and also to form a grip for the device I provide an enclosing frame of insulating material. The frame shown comprises the end or head 33 whose outer part is conical and whose base 33' is exteriorly threaded and secured against the yoke plate 12 concentric 95 therewith. This frame end has the axial passageway 34 through which the tool sup- 100

porting rod 20 extends. The enclosing frame part in the form of a shell 35 is of an internal diameter to pass readily over the insulating block 24, and at its front end is 5 threaded to receive the threaded base 33' of the frame end 33. At its outer end the sleeve or shell has the opening 36 for receiving the terminal pins 25 and 26, and to protect against the entrance of moisture or dust, a 10 washer 37 of rubber or other sealing material is interposed between the sleeve end and the block 24. To prevent entrance of moisture or dirt through the passageway 34 in the frame part 33 a sealing member 38 which 15 may be a short length of soft rubber tubing, surrounds the rod 20 and abuts against the plate 12 across the hole 21 but clear of the sides of the passageway 34.

The device is light and compact and can 20 be conveniently used. The yoke and end plates 12 and 13 which are rigidly secured to the ends of the magnet legs 10 and 12 form a strong framework on which the other parts are supported and mounted. The winding 25 terminals are securely anchored so that a connecting plug can always be quickly and readily applied thereto. The armature abutments in the form of rubber tube lengths can be readily applied or replaced and adjusted relative to the armature. The sealing washer 37 and the sealing tube 38 will entirely close the housing against the entrance of moisture and dirt to the interior, and the windings and electrical circuits will there- 30 fore be fully protected.

I claim as follows:

1. In a device of the class described, the combination of a magnet frame comprising a yoke plate and legs extending therefrom, said frame being polarized, an armature bar having its outer end exposed to the poles of said magnet frame, a spring secured to said yoke plate and said armature bar for supporting said bar for vibration, a tool supporting rod extending from said armature bar, and an energizing winding carried by said armature bar.

2. In a device of the class described, the combination of a permanent magnet frame 50 comprising a yoke and legs extending therefrom, an armature bar flexibly attached to said yoke to vibrate between said legs with its outer end opposed to the poles of said frame, a tool supporting post extending 55 from the attached end of said armature bar, an energizing winding on said armature bar, a plate of non-magnetic material secured to the pole ends of said legs, and cushioning abutments for said armature bar extending 60 from said plate.

3. In a device of the class described, the combination of electro-magnet structure comprising a yoke, magnetizable legs extending 65 parallelly from said yoke, an armature bar spring hinged to said yoke and extending

parallel with said legs, said armature at its end having polarity cooperation with said legs, an energizing winding for changing the polarity relationship between said armature and legs, a plate adjacent to the armature 70 end, pins extending from said plate, the armature end being adapted to swing between said pins, and rubber cushioning tubes on said pins for receiving the impact of the vibrating armature during current 75 flow thru the winding.

4. In a device of the class described, the combination of a yoke plate, bars extending parallelly from said yoke plate and forming with said plate, a magnet frame, a non-magnetic plate secured to the outer ends of 80 said bars, an armature extending parallelly with said bars and spring hinged to the yoke plate, an energizing winding for varying the relative polarity of the armature and 85 magnet frame whereby said armature will be vibrated, a tool supporting post extending parallel with said bars and secured at its inner end to the armature near the hinged end thereof, said yoke plate having an opening 90 through which said post extends, and a short length of soft rubber tubing surrounding said post and engaging against said yoke plate to prevent travel of moisture, dust or dirt along said post and through the 95 opening in said yoke plate.

5. In an electric safety razor, the combination of a supporting plate, an armature bar having spring support on said plate and extending therefrom, a tool post parallel 100 with said bar and secured at its inner end thereto to vibrate therewith, means for vibrating said armature bar, said supporting plate having an opening through which said post extends, and a short length of soft 105 rubber tubing surrounding said post and engaged against said supporting plate to seal said plate opening.

6. In an electric safety razor, the combination of a frame forming a grip, a vibrating bar within said frame, said frame having an opening to the exterior, a tool supporting 110 post extending from said bar through said opening to transmit the vibration of said bar to a tool on said post, a soft rubber washer 115 surrounding said post in front of said opening to seal said opening against entrance of moisture, dust and other foreign matter.

7. In a device of the class described, the combination of a magnet frame comprising a 120 yoke plate and parallel legs extending therefrom, an armature extending parallel with said legs and supported from the yoke plate to vibrate, a tool supporting post extending parallel with said magnet frame and secured 125 to the armature to partake of the vibration thereof, an energizing winding for causing variations in the relative polarity of said frame and armature for causing the vibration of the armature, a support secured to 130

the pole ends of said magnet frame, terminal pins extending with their outer ends parallel with and adjacent to the axis of said support, intermediate sections of said pins extending diagonally to said support and the inner ends extending parallel with but displaced from the plane of the outer ends of the pins, a spacer block receiving the inner ends of the pins, the terminals of said energizing winding being secured to said pins. ¹⁰ In witness whereof, I hereunto subscribe my name this 20 day of August, 1926.

SAMPSON W. MOON.
